WIRE LINE CORE BARREL

John Karich and Albert F. Pickard, Minneapolis, Minn.,
assignors to E. J. Longyear Company, Minneapolis,
Minn., a corporation of Delaware

Filed Nov. 27, 1964, Ser. No. 414,218
33 Claims. (Cl. 175—247)

This invention relates to the art of deep core drilling in earth formations and to improvements in wire line core barrel apparatus for recovering cores. More particularly, this invention relates to new and novel apparatus for positively locking the latch elements of the core barrel inner tube assembly in a drill stem latch seat until the latch release member has been retracted through the use of an overshot assembly; and additionally to new and novel valving means utilizable with the aforementioned apparatus so that core barrel inner tube assembly may be fluidly propelled to the bit end of the drill stem regardless of the drilling direction and thereafter provides an open fluid bypass channel. Further this invention relates to new and novel valving means for an overshot assembly.

This invention has been made in order to provide water line core barrel equipment for overcoming problems of the nature set forth hereinafter which are encountered in using core barrel equipment of the prior art. One of the problems encountered in using water line core barrel equipment of the prior art is that after substantial use, the axially and radially outward corners of the latch elements become worn as does the corners of the ledge flange of latch seat of the drill stem against which the latch elements abut to normally preclude the core barrel inner tube assembly moving axially outwardly. As a result of this wearing, the latch elements will not always retain the core barrel inner tube assembly adjacent the drill bit core during the time a core sample is being drilled.

Additionally with hydraulically propellable wire line core barrels of the prior art having fluid bypass channels that have at least a portion of the axial length thereof located within the confines of one of the elements of the assembly, and a valve member movable between positions adjacent said location to open said channel when the assembly is in a core taking position and closing the channel to permit fluidly propelling the assembly to the bit end of the drill stem; at times due to drilling into pockets having fluid, for example, water under high pressure, the back pressure will operate the latch release element to release the latches from the latch seat. That is with the prior art hydraulically propellable core barrel assemblies, the open fluid bypass channel adjacent the latch release element has a restricted portion which is not of sufficient cross sectional area to permit the back flow of fluid without, at times, moving the latch release element to a latch releasing position. To increase the cross sectional area of a fluid bypass channel in such prior art core barrel assemblies would result in structurally weakening the assembly. In the present invention this problem is overcome by providing annular fluid bypass channel radially between the drill stem and the core barrel inner tube assembly, and a core barrel assembly valving member movable between a position substantially forming a fluid seal with the drill stem and a position providing a clearance space of a transverse cross sectional area of about the same size as the cross sectional area between, for example, the major portion of the core barrel inner tube and the drill stem to permit back flow of fluid without operating the latch release element, even when the assembly is in a latched operating position. Further the structure for

2

providing the aforementioned valving action is much cheaper to manufacture than that of the prior art.

One of the objects of this invention is to provide new and novel apparatus for releasably, lockingly retaining the latch elements of a wire line core barrel inner tube assembly in a latched seated position. Another object of this invention is to provide new and novel means to constantly resiliently urge the latch elements and latch release element to a latch seated position.

A further object of the invention is to provide in a wire line core barrel assembly, new and novel mechanism for hydraulically propelling the assembly to the bit end of the drill stem; and upon the assembly latchingly engaging the drill stem, permitting fluid to readily bypass the assembly. Another object of the invention is to provide new and novel valving mechanism in a wire line core barrel assembly to permit fluidly propelling the assembly to the bit end of the drill stem regardless of the drilling direction, and which permits fluid to readily bypass the assembly when the assembly is being retracted through the drill stem. A still further object of this invention is to provide flexible annular members on a core barrel inner tube assembly and also on an overshot assembly to provide for hydraulically propelling the respective assembly to the bit end of the drill stem and to permit fluid bypassing the assemblies when they are being retracted.

Other and further objects are those inherent in the invention herein illustrated, described and claimed and will become apparent as the description proceeds.

To the accomplishment of the foregoing and related ends, this invention then comprises the features herein-after fully described and particularly pointed out in the claims, the following description setting forth in detail certain illustrative embodiments of the invention, these being indicative, however, of but a few of the various ways in which the invention may be employed.

For purposes of facilitating the description of the invention, the term "inner" refers to that portion of the drill stem, or of the assembly, or an element of the assembly being described which in its position "for use" in the drill stem is located closer to drill bit on the drill stem than any other portion of the apparatus being described, except where the term clearly refers to a transverse circumference, direction or diameter of the drill stem or other apparatus being described. The term "outer" refers to that portion of the drill stem, or of the assembly, or element being described which in its position "for use" in the drill stem is located closer to the mouth of the drill hole than any other portion of the apparatus being described, except where the term clearly refers to a transverse circumference, direction or diameter of the apparatus being described.

The invention is illustrated in the drawings in which corresponding numerals refer to the same parts and in which:

FIGURES 1-3 one arranged above the other with the axial center lines aligned and lines A—A of FIGURES 1 and 2 aligned, and lines B—B of FIGURES 2 and 3 aligned, form a composite longitudinal section through the first embodiment of core barrel inner tube assembly of this invention and the drill stem when the assembly is in a latched core taking position;

FIGURE 4 is a fragmentary cross sectional view of an outer end of the first embodiment of core barrel inner tube assembly as it is being retracted through the drill stem, said view generally showing the same structure of the core barrel inner tube assembly as FIGURE 1, but in a retracted condition;

FIGURE 5 is a fragmentary view of an upper end portion of the first embodiment of the core barrel inner tube assembly being dropped through the drill stem to the bit end thereof, said view generally illustrating the same structure of the assembly as shown in FIGURE 1 but with the parts in a different relative position;

FIGURE 6 is a cross sectional view generally taken along the line and in the direction of arrows 6—6 of FIGURE 1 to show the relative positions of the latches releasably locked in the latch seats;

FIGURE 7 is a cross sectional view of the upper end portion of the second embodiment of the core barrel inner tube assembly of this invention as it is being fluidly propelled through the drill stem toward the bit end thereof, the construction of the second embodiment of core barrel inner tube assembly axially inwardly of line E—E of FIGURE 7 being the same as the construction of the first embodiment axially inwardly of line B—B of FIGURE 2;

FIGURE 8 is a fragmentary view of the portion of the core barrel inner tube assembly of the second embodiment outwardly of line D—D of FIGURE 7 other than it illustrates the spear point valving mechanism of the core barrel inner tube assembly in the latched seated core receiving position; the solid line position of the flexible washer showing normal fluid bypass, and the dotted line position showing the flowing thereof when fluid pressure is exerted in the opposite direction;

FIGURE 9 is a view similar to FIGURE 8 other than it illustrates the initial retraction of the valving mechanism, but prior to the time the latch release tube has moved sufficiently to retract the latches out of latching engagement with latch seat;

FIGURE 10 is a view similar to FIGURE 9 other than it illustrates the relative positions of the elements at outer axial end portion of the core barrel inner tube assembly at the time the latch release tube has been moved to a fully retracted position and the latch body moves axially outwardly relative to said tube through the action of the coil spring;

FIGURE 11 is a cross sectional view generally taken along the line and in the direction of arrows 11—11 of FIGURE 7 to illustrate the flexible washer in a core barrel inner tube assembly fluid propelled position;

FIGURE 12 is a longitudinal cross sectional view of the overshot assembly of this invention as it is being fluidly propelled toward the bit end of the drill stem;

FIGURE 13 is a fragmentary view of the structure of FIGURE 12 other than it illustrates the relative positions of the elements of the overshot assembly as said overshot assembly is being retracted in the drill stem;

FIGURE 14 is a cross sectional view generally taken along the line and in the direction of the arrows 14—14 of FIGURE 12 to illustrate the flexible washer forming a fluid seal with the drill stem;

FIGURE 15 is a view similar to the upper end portion of FIGURE 7 other than it illustrates another embodiment of the valving structure and the mounting thereof;

FIGURE 16 is a cross sectional view illustrating the outer end portion of the first embodiment of the core barrel inner tube assembly in a "jammed" condition in a downwardly extending drill stem, the inner end portion of an overshot assembly used for lowering the core barrel inner tube assembly, and the inner end portion of a tube for releasing the pulling dogs from a spear point plug coupling condition; and

FIGURE 17 generally illustrates the same structure as FIGURE 16 other than showing the relative positions after the core barrel inner tube assembly has latched in a core taking position such as illustrated more fully in FIGURES 1—3.

Referring now in particular to FIGURES 1—3, the first embodiment of the invention of the wire line core barrel inner tube assembly will now be described, said

assembly being generally designated 10. Even though in FIGURES 1—3 the assembly 10 is illustrated generally in a horizontal condition, it is to be understood that it is utilized when the drilling direction is vertically downwardly or inclined downwardly sufficiently that the assembly will free fall to the bit end of the drill stem generally designated 11 in a manner described in U.S. Patent 2,829,868 to Pickard et al. The drill stem 11 is made up of sections of pipe coupled together and having an annular drill bit 12 mounted on the inner end thereof.

The portion of the drill stem attached to or extending below pipe section 11a is commonly referred to as the core barrel outer assembly and is provided for receiving and retaining the core barrel inner tube assembly, generally designated 10. The core barrel outer tube assembly is composed of a core barrel outer tube 18, a reaming shell 19 threadedly connected to the inner end of the tube 18, said shell having a hardened material such as diamonds (not shown) on the transverse outer reaming surface and on the annular drill bit 12 for drilling into earth formations from which the core sample is taken. The bit 12 is threadedly connected to the inner end of the reaming shell.

The outer end of the core barrel outer tube assembly includes a locking coupling 20 which connects said assembly to the adjacent pipe section 11a of the drill stem. At the opposite end of the coupling 20 from the aforementioned pipe section, a guide coupling 21 is threadedly connected. The inner end of the locking coupling in conjunction with the annular recess 21a of the guide coupling formed a seat in the guide coupling against which the detents or latch dogs 16 of the core barrel inner tube assembly are seated for removably retaining the assembly 10 adjacent the core bit. Also the inner end portion of the locking coupling has an inwardly projecting flange 20a which extends as a partial cylindrical surface in the recess 21a. The side face of this flange bears against a surface of the latch dog and causes said latch dog and other portions of the core barrel inner tube assembly to rotate with the drill stem when the latch dogs are in a latch seated position such as illustrated in FIGURE 1.

The opposite end of the guide coupling is threadedly connected to the outer end of the core barrel outer tube 18, the core barrel outer tube having an annular recess 18a to receivably mount a landing ring 23 in abutting engagement with the guide coupling (see FIGURE 2). As may be noted, the inner diameter of the landing ring is sufficiently smaller than the inner diameter of the remaining portion of the drill stem described heretofore to form a suspension shoulder in the core barrel outer tube. Since the core barrel outer tube is generally of a construction illustrated and explained in greater detail in U.S. Patent 3,120,282, issued Feb. 4, 1964, other than for the provision of the landing ring instead of a suspension flange and a substantially longer locking coupling, it will not be described in greater detail.

The core barrel inner tube assembly 10 includes a latch body 26 having a pair of latches 16 and a latch insert block 17 mounted thereon, a latch release tube 27 for retracting said latches, a core sample receiving tube 28, an inner tube cap 29 threaded into the outer end of the core barrel receiving tube, and a spindle 36 for connecting the cap to the inner end portion of the latch body for limited relative slidable movement. The core receiving tube has a replaceable core lifter case 31 threaded on the opposite end thereof and a core lifter 32 mounted in the core lifter case. The structure and function of the core lifter case and core lifter are generally of the nature set forth in U.S. Patent 2,829,868 and therefore will not be further described.

The cap 29 has a fluid passageway 34 that at one end opens to the interior outer end of the core receiving tube and at the opposite end to the annular clearance space between the core barrel inner tube assembly and the core barrel outer tube 18 that forms a part of the fluid channel

to permit fluid to bypass core barrel inner tube assembly when it is in core taking position such as illustrated in FIGURES 1-3. The cap 29 also includes an axially elongated bore 40 for receiving the inner end portion of the spindle 36. A grease fitting 41 is threaded into the opposite reduced end portion of the bore 40. A bearing 42 is mounted on the spindle in abutting engagement with the inner end of the bearing housing 38 which is also slidably mounted on said spindle and threaded connected to cap 29; there being provided a coil spring 43 that at one end abuts against said bearing and at the opposite end against a nut 44 threaded on the inner end of the spindle. The spring 43 resilient urges the spindle towards the core receiving tube while retaining bearing 42 in abutting engagement with the bearing housing 38.

The bearing housing includes an outwardly extending annular flange for receivably mounting the thrust bearing assembly 46 in abutting relationship with the metal spacer washer 47. A pair of resilient shut off valve washers 48 are mounted on the spindle with a second metal space washer 49 intermediate washers 48. The shut off washer opposite the bearing 46 is mounted in abutting relationship with enlarged diametric annular member 39 which in turn abuts against a shoulder formed on the spindle. The outer end of the spindle is threaded into the threaded inner portion of the axially extending bore 50 of the latch body. A lock nut 51 is threaded onto the aforementioned end portion of the spindle to abut against the lower end of the latch body.

Referring to FIGURE 2 it is to be noted that the latch body has a diametric portion 60 of an outside diameter to fit within a centralizer ring 23 and a maximum diameter portion 26a to form with portion 60 a shoulder 61 seatable against said centralizer ring for supporting the core barrel inner tube assembly out of contact with the drill bit. Latch body portion 60 has an annular groove 58 for mounting an O-ring 59 that forms a fluid seal with the centralizer ring such as illustrated in FIGURE 2. To be mentioned is that all portions of the core barrel inner tube assembly axially inwardly of shoulder 61 are of diameters smaller than the minimum inside diameter of ring 61 in order that said portions may pass through the centralizer ring.

A plurality of circumferentially spaced, transversely extending outlet ports 56 are provided in the latch body to open to the bore 50 and to the annular space between the core barrel inner tube assembly and the core barrel outer tube axially inwardly of the centralizer ring 23 when said assembly is in a latched core taking position. A second plurality of ports 55 are formed in the latch body to at their one ends open into the bore 50 and at the opposite ends of the annular fluid channel between the drill stem and the core barrel inner tube assembly, but on the opposite axial side of the centralizer ring from ports 56. The ports 55, ports 56, and the portion of the bore 50 intermediate said ports provide a channel to permit fluid bypassing the centralizer ring when the shoulder 61 is seated on said ring, the diameter of ports 56 being less than the axial height of the cylindrical portion of the centralizer ring.

A generally rectangular slot 67 is formed in the outer reduced diameter portion of the latch body axially outwardly of ports 55 and has a through pin 68 extended therethrough and into appropriate apertures in the latch body for pivotally mounting the latch dogs 16 in side by side relationship. The diameter of the apertures in the latch dogs through which pin 68 is extended is slightly larger than the diameter of said pin in order to permit the bottom curved portions of said latch dogs moving into and out of engagement with the curved surface of the insert block 17 which is also mounted in a slot 67. A pin 66 is extended through the insert block and into appropriate apertures in the latch body for retaining said block in said slot. The construction of the latches 16 is substantially the same as that described in U.S. Patent 3,103,981, granted Sept. 17, 1963 other than for the provision of apertures

for mounting rivets to attach springs and the differences noted hereinafter.

Mounted on the outer reduced diameter portion of the latch body for slidable movement between a position abutting against the shoulder 65 and a position axially spaced therefrom is the latch release tube 27. Tube 27 has a slot 70 radially opposite each of the latch dogs so that an outer corner portion of each latch dog may be extended therethrough to latchingly engage the latch seat 21a. A torsion spring 71 within slot 67 has one end of one leg bent to be retained in an aperture formed in the outer central portion of one latch dog, and the outer end of the second leg being bent to be retained in a corresponding position of the other latch dog, whereby it resiliently urges the latch dogs to pivot about through pin 68 to extend through the respective slot 70 and to a position to latchingly engage the latch seat such as illustrated in FIGURE 1.

A right angle cut out 16a is provided in an outer corner 20 of one of the latch dogs and an oppositely faced cut out 16b of the substantially same size is formed in the other latch dog, the cut outs being located to form a generally rectangular, open ended slot when the latch dogs are spread apart to a latching position such as illustrated in FIGURE 1. An axially elongated slot 74 is formed in the latch body on either side of the slot 67 to extend transverse thereto, the slots 74 having a cross sectional dimension substantially equal to the spacing between axially extending edges of the cut outs 16a, 16b. A through pin 75 is 25 extended through the slots 74, and has its opposite ends mounting retained within opposed apertures in the latch release tube so as to be moved therewith. The diameter of the pin 75 is slightly smaller than that necessary to retain edges 16c of the latch dogs in abutting engagement 30 with the peripheral wall of the guide coupling which forms the latch recess when the pin bears against opposite axial edges of the slots 16a, 16b as illustrated in FIGURE 1. The slots 74 extends axially inwardly sufficiently 35 such that when the pin 74 abuts against the inner curved edges thereof, the pin is located slightly axially outwardly of the transverse edges of slots 16a, 16b and the inner annular edge of the latch release tube abuts against the shoulder 65. The axial length S of the slots 74 is sufficient 40 so that when the pin 75 is moved outwardly to abut against the oppositely curved edges thereof, the latch release tube has fully retracted the latch dogs (see FIGURE 4). Thus the length of the slots 74 limit the amount of axial movement of the latch release tube relative to the latch body.

50 The outer end portion 26c of the latch body has a threaded aperture that opens to the rectangular slot 67 for threadedly mounting an elongated bolt 77 to extend axially outwardly of the latch body and centrally within the confines of the latch release tube. A transversely extending bar 78 is welded to the latch release tube in position to bear against the axially outermost surface of the latch body when the lower edge of the latch release tube seats against shoulder 65, the latch release tube having apertures of diameters to open on either side of said bar. The 55 bar 78 has an aperture through which the bolt 77 is extended, there being provided a tubular guide 79 on the bolt which is also slidably extended through the aperture of the bar 78. The guide 79 has a flange at its outer axial end that bears against the head of the bolt 77, there being provided a coil spring 80 that at one end bears against said flange and at the opposite end bears against the bar 78 to resiliently urge the latch release tube to a position that its inner annular edge abuts against the shoulder 65. Accordingly through the provision of the bolt 77 which is attached to the latch body for movement therewith, the bar 78 which is attached to the latch release tube for movement therewith and the coil spring 79, the latch release tube is resiliently retained in a position relative to the latch body 65 as shown in FIGURE 1 wherein through pin 75 is lo-

cated wthin the cutouts 16a, 16b of the latch dogs for locking said latch dogs in a latch seated condition.

A plug, generally designated 84, having an axially elongated transverse slot 86 is slidably mounted in the outer end of the latch release tube by a pin 87 secured in said tube and extended through said slot. The plug has a spear point 88 extending outwardly beyond the latch release tube and a main body portion 85 to form a somewhat close sliding fit within the inner peripheral wall of the latch release tube, said main body portion having the aforementioned slot 86 formed therein and being integrally connected to the spear point.

The relative location of the pin 87, the slot 86 in the plug, and the axial dimension of the slot 86 are such that when the latch release tube abuts against the latch body shoulder 65, the pin 87 is a little outwardly of the inner transverse edge of the slot, and the inner surface 84a of the plug abuts against the head of the bolt 77. In this connection note that an adjustment is provided in one direction due to the threading of the bolt 77 into the latch body.

The structure of the first embodiment of the wire line core barrel assembly of this invention having been set forth, the structure of the second embodiment of the wire line core barrel inner tube assembly, generally designated 100, will now be set forth (see FIGURES 7-11). The assembly 100 is of the same construction as assembly 10 other than for the provision of the modified spear point plug and the structure mounted thereon. That is embodiment 100 includes a latch body 26, latch dogs 16 pivotally mounted thereon and a latch release tube 27 together with a plug generally designated 104 having a rectangular slot 105 through which the through pin 87 is extended to mount the plug for limited slidable movement relative the latch release tube. The slot 105 is located in the main body portion 106 of the plug, the outer end of the main body portion being integrally formed with a non-threaded intermediate diameter portion 107. Portion 107 in turn is integrally joined to threaded portion 108 and is of substantially the same diameter, portion 108 in turn being integrally connected to the minimum diameter portion 109. At the outer end of portion 109 there is integrally joined a spear point 110.

As may be noted, at the juncture of portions 105 and 107 there is formed a shoulder 111, the shoulder 111, the shoulder 11 being at the same elevation as the outer annular edge 27a of the latch release tube when the outer transverse edge of the plug slot abuts against pin 87. As a result the leather washer 112, which is approximately the same axial thickness as the plug portion 107, extends generally radially in abutting relationship with the latch release tube to form a fluid seal between the plug and the inner peripheral wall of the drill stem. In this connection, it is to be mentioned that the outer diameter of the latch release tube and the outer diameter of the latch body is sufficiently smaller than the inner diameter of the drill stem to provide a fluid bypass channel between the core barrel inner tube assembly and the drill stem axially between the leather washer and the inlet ports 55 of the latch body.

In order to retain the inner annular portion of the leather washer in abutting engagement with the shoulder 111, a retainer nut 116 is threaded onto portion 108. A lock nut 117 is also threaded on portion 108 in abutting engagement with the retainer nut 116. The retainer nut has a beveled surface 116a (see FIGURE 8) that provides a radially extending annular surface 116b having approximately the same outside diameter as the outside diameter of plug portion 106 for clampingly retaining the inner annular portion in a fixed position relative the plug. As a result of the provision of the beveled surface, there is provided a recess into which the outer annular portion of the leather washer may bend to the dotted line position of FIGURE 8 in order to permit a back flow of

fluid under pressure without causing the unlatching of the latch dogs in the event the drill bit cuts into a pocket of high pressure fluid. In this connection it is to be mentioned that other than the leather washer and the enlarged diametric portion of the latch body (same as 26a for the first embodiment), the maximum diameter of any portion of the core barrel inner tube assembly 100 inwardly of said enlarged diametric portion is not greater than the maximum diameter of any portion of assembly 100 outwardly of said enlarged diametric portion. Additionally, other than for the leather washer, the area of the portion of the fluid bypass channel 50, 55, 56 is substantially the same as the minimum area of the bypass channel at any axial location of assembly 100 axially outwardly of ports 55 and axially inwardly of ports 56 (see portion of the first embodiment) inwardly of lines A-A of FIGURES 2 and 3.

For retracting wire line core barrel inner tube assemblies, including the first and second embodiments described herein, the overshot assembly, generally designated 125, has been provided (see FIGURES 12-14). The overshot assembly 125 is generally cylindrical in shape and is made up of a main body 126 and a valving portion 127. The main body includes a generally cylindrical overshot body 128 that has an elongated slot 129 milled in the inner central portion thereof to form two spaced overshot body segments 128a. The transverse cross sectional area of each of the segments is similar in shape but the segments are located 180° relative to one another. The longitudinal length of the slot extends outwardly to the line 128b. A pair of pulling dogs 131 are disposed in face to face relationship in the slot 129; and are pivotally mounted on the pin 133 which extends through the overlapping hub portions of the pulling dogs, and is secured in the overshot body segments. A coil spring 134, which is seated on the pins 135 (there being one pin welded on the outer ends of each pulling dog), normally urges the outer ends of the pulling dogs apart, and thus urges the jaws together in a grasping position while permitting expansion of the dog jaws to slide over the spear point of a core barrel inner tube assembly when the overshot body has been moved adjacent the bit end of the drill stem.

A frusto conical shoulder 136 formed on the inner end of the overshot body aids in centering the overshot assembly over the spear point, the inner surfaces of said shoulder being similarly shaped and slightly larger than the generally frusto conical portion inwardly of the spear point of the inner tube assembly to be retracted. When the spear point is retained between the jaws 135, the shoulder imparts stability to the entire core barrel inner tube assembly as the inner tube and overshot assemblies are retracted through the drill stem.

The overshot body is of a reduced diameter at 128c from a location a short distance inwardly of the outer ends of the latch dogs to the outer end thereof. An axial bore 138 is formed in the reduced diameter portion 128c from a location axially spaced from the line 128b to the outer end thereof.

An elongated tube is mounted on the reduced diameter portion 128c to have the inner annular edge generally co-extensive with the line 128b and secured to the overshot body by shear pins 140. A bar 142 having a central aperture therethrough is welded into tube 139 similar to the welding of bar 78 to the latch release tube, the bar being located axially outwardly of the outer end of the overshot body.

The valving portion 127 includes a fitting 144 having an axially central, enlarged diametric portion 144a of a diameter to form a relatively close fit with the outer end of the tube 139. In order to mount the valving portion for a limited slidable movement relative to the tube 139, the diametric portion 144a is provided with the slot 145 through which a transverse pin 143 is extended, pin 143 being secured in apertures in the outer end of the tube 139.

Joined to the inner end of diametric portion 144a is a rod 144b that is threaded at the inner end, there being a washer 148 on said rod and a nut 149 threaded thereon to limit the inward movement of the washer. A coil spring 150 is provided on the rod such that the outer end abuts against the bar 142 and the inner end abuts against the washer 148 to resiliently urge the fitting to move to position that the pin 143 abuts against the outer transverse edge of the slot 145. A non-threaded intermediate diameter portion 144d is integrally joined to the enlarged diametric portion 144a to form an annular shoulder 154, the opposite end of portion 144d in turn being integrally joined to the threaded outer end portion 144e of the fitting. A retainer nut 157 (same construction as nut 116) is threaded on portion 144e to retain the flexible leather washer 156 is abutting relationship with the shoulder 154 in a manner that the leather washer of the second embodiment of the core barrel inner tube assembly is retained against the shoulder 111. Thus when the pin 143 abuts against the outer edge of the fitting slot 145, the washer 156 extends generally radially in abutting relationship with the outer annular end 139a of the tube 139 to at least substantially form a fluid seal with the drill stem.

A coupling element 158 is threaded onto the fitting portion 144e to have the inner end thereof abut against the retainer nut 157, the coupling element being generally tubular shaped and closed at its outer end by a cap portion 158a. The cap portion has an aperture formed therein for a wire line cable 159 to be passed therethrough and knotted or otherwise fastened.

A plurality of axially elongated, radially extending circumferentially spaced lands 158b are joined to the outer surface of the coupling element to permit fluid bypassing the coupling element while at the same time form guides for the overshot assembly as it is moved through the drill stem. To be mentioned is that all portions of the overshot assembly other than for the washer 155 and the land 158b are of maximum diameters relative to the inner diameter of the drill stem to provide an annular channel to permit fluid to bypass the overshot assembly in the drill stem.

When the valving portion is retracted relative the main body as illustrated in FIGURE 13, fluid flowing in an inward direction or the outward movement of the overshot assembly through the drill stem will cause the leather washer 156 to flex and thereby provide an open fluid channel from one axial end of the overshot assembly to the other, as will be more fully set forth hereinafter.

The structure of both embodiments of the wire line core barrel inner tube assembly and the overshot assembly having been described, the operation thereof will now be set forth. First the operation of the first embodiment of the core barrel inner tube assembly will be described.

For purposes of facilitating the description and operation of the inner tube assembly 10, it will be assumed that the drill stem is extended into a hole in an earth formation in a generally vertical downward direction and that the core barrel inner tube assembly is about to be inserted into the drill stem for continuing the taking of core samples. The core barrel inner tube is inserted into the outer end of the drill stem, the latch release tube being moved axially outwardly relative to latch body against the resilient action of spring 80 to a position such as illustrated in FIGURE 4 to first move the lock pin 75 out of the latch cut outs 16a, 16b and thence retract the latches. After the core barrel inner tube assembly has been moved into the drill stem sufficiently that the latch dogs are located in the confines thereof and no outward force applied to plug 84, the spring acting through bar 78 and bolt 77 causes the latch release tube to move inwardly relative the latch body to the position illustrated in FIGURE 5. In moving to this position, the beveled edges of the slot in the latch release tube permit the latch dogs to be moved apart about the axis of pivot pin 68 under the action of the torsion spring 71, the inner per-

ipheral wall of the drill stem limiting the aforementioned pivotal movement of the latch dogs. However at this time the inward movement of the latch release tube toward the shoulder 65 is limited by the pin 75 abutting against the outer transverse edges 16e' of the latch dogs, the adjacent axial edges of the latch dogs not having moved sufficiently far apart to permit the lock pin 75 to move into the slot formed by cutouts 16a, 16b.

When the core barrel inner tube assembly has moved in the drill stem to a position that the suspension flange 61 of the latch body seats against the shoulder provided by the centralizer ring, the outer corners of the latch dogs are opposite the latch seat in the drill stem. At this time, or upon slight rotation of the drill stem, the latch dogs pivot into the latch seat due to the resilient action of the spring 71. This pivotal movement of the latch dogs spreads the axial extending edges of cut outs 16a, 16b sufficiently that the pin 75 can move there between. Either through the action of gravity and/or in conjunction with the resilient action of spring 80, the latch release tube is then forced to move relative to the latch body to position pin 75 in the cut outs 16a, 16b as illustrated in FIGURE 1. The movement of the locking pin into the cut outs thereupon prevents the latch dogs being retracted from the latch seat until the time that the latch release tube has been moved sufficiently axially outwardly relative the latch body that the pin 75 is clear of the cut outs 16a, 16b. Accordingly, even if the outer transverse corners along edge 16c of the latch dogs and/or the inner corner of the radially extending ledge of the latch seat against which edges 16c normally abut are worn slightly, the thus tapering of the surfaces due to wearing will not provide inclined surfaces whereby an outward pressure on the core barrel inner tube can force the latch dogs to a latch release position. As added insurance, the coil spring 80 resiliently urges the latch release tube to remain in a position relative the latch body such as shown in FIGURE 1.

Assuming now that the core barrel is filled with core and the shut off valve washers 48 have been compressed to provide a high pressure signal at the outer end of the drill stem, the drill stem is pulled axially outwardly. In the event the core is not broken, the core barrel inner tube will remain in position until the annular shoulder of the drill bit abuts against the core lifter case 31. This movement of the drill stem relative the core barrel inner tube and case 31 is permitted through the provision of the coil spring 43 and the bearing housing being mounted for limited slidable movement relative the spindle 36. Thus the force necessary to break the core is transmitted from the drill stem directly to the core lifter case.

To withdraw the core barrel inner tube assembly 10, a conventional overshot assembly or the one illustrated in FIGURES 12-14 is used. Assuming the overshot assembly is of a type to be lowered by a wire line cable and moves to the bit end of the drill stem through gravity, after the overshot jaws of the overshot assembly have clampingly coupled onto the spear point 88, the overshot assembly is retracted through the wire line. The initial retraction of the plug 84 will move it outwardly relative to the latch release tube to a position that the inner transverse edge of the slot 86 abuts against the pin 87. At that time further retraction of the plug will cause the latch release tube to also be retracted in the direction of the arrow 90 which results in the spring 80 being compressed but no movement of the latch body or the latch dogs takes place until the beveled edges of the slots 70 of the latch release tube abut against the diagonal edges of the latch dogs. At the time the aforementioned beveled edges bear against the latch dogs, the locking pin 75 has been moved by the latch release tube sufficiently outwardly from the inner curved edges of the slots 74 to be axially outwardly of the edges 16e of the latch dogs. Additional retraction of the latch release tube now forces the latch dogs to pivot about the latch pin 68 against the resilient

action of the torsion spring and thereby completely retract the latch dogs from the latch seat. The relative positions of the latch dogs, the outer portion of the latch body, the latch release tube, the plug 84 and associated structure when the latch release tube has been fully retracted relative the latch body are illustrated in FIGURE 4. In this connection it is to be noted that at this time the locking pin 75 abuts against the outer axial edge of the slot 74 to transmit the retracting force from the latch release tube to the latch body. Also after the core is broken the spring 43 will usually urge the bearing housing and the parts depending therefrom to move relative the spindle 36 to generally the position illustrated in FIGURE 2. The actual position depending on the spring characteristics and the weight of the core.

The operation of the first embodiment of the wire line core barrel inner tube assembly having been described, the operation of the second embodiment 100 will now be set forth. Since the construction of the second embodiment wire line core barrel inner tube assembly inwardly the line E—E of FIGURE 7 is the same as that inwardly of line E—E of FIGURES 1-3 for the first embodiment, that portion of the second embodiment has not been illustrated nor will the operation thereof be set forth. Likewise since the portion of the wire line core barrel inner tube assembly 100 intermediate line D—D and E—E of FIGURE 7 is the same as that between the same lines of FIGURE 5 for the first embodiment, the functions of this portion of the second embodiment will only be briefly referred to.

The second embodiment is hydraulically propellable to the bit end of the drill stem regardless of the drilling direction, for example upwardly, downwardly, or at any angle relative to the horizontal. When the core barrel inner tube assembly 100 is to be fluidly propelled to the bit end of the drill stem, it is inserted into the outer end of said drill stem. After the assembly has been inserted in the drill stem and fluid pressure is exerted in an inwardly direction (arrow 124) in against the valving portion i.e. plug 104 and members 117, 112, or the drilling direction is at an angle below the horizontal, the relative position of the elements at the outer end of the core barrel inner tube assembly are generally as shown in FIGURE 7. That is, the locking pin 75 abuts against the edges 16e of the latch dogs and thereby prevents the latch release tube 27 moving relative to the latch body to a position to abut against the shoulder 65. However the coil spring 80 is resiliently urging the latch release tube to move to this position.

After fluid under pressure has been pumped into the drill stem outwardly of assembly 100, fluid pressure acting against the valving portion 104, 112, 117 moves the valving portion so that the outer edge of the slot 105 abuts against the connecting pin 87, provided portion 104 has not already moved to this position. Now the inner axial surface of the plug is either abutting against the head of bolt 77 or slightly axially spaced therefrom while the leather washer 112 has been moved to abut against the outer annular edge 27a of the latch release tube. The outer annular edge of the latch release tube in conjunction with the shoulder 111 provides a sufficient supporting surface so that the outer annular edge portion of the leather washer does not flex inwardly to permit any substantial quantity of fluid bypassing the core barrel inner tube assembly at the washer. In this connection it is to be noted that the outer diameter of the leather washer advantageously is of very slightly greater dimension than the inner diameter of the core barrel inner tube assembly to provide a better fluid seal therewith. Also, the washer 112 may be made of rubber or other material as long as it has sufficient rigidity to extend radially to form a fluid seal with the drill stem in the position illustrated in FIGURE 7 and will flex as illustrated in FIGURE 8 under normal fluid pressure when fluid is pumped into the drill stem during the time a core sample is being drilled.

Fluid pressure acting against the outer exposed surface of the leather washer, the outer annular surface of the retaining nut 117, and the corresponding surfaces of the plug fluidly propel the assembly 100 to the bit end of the drill stem regardless of the drilling direction. At the time the assembly 100 has moved to a position that the latch body ledge flange abuts against the centralizer ring (same as that illustrated in FIGURE 2 for assembly 10), the latch dogs pivot outwardly to latchingly engage the latch seat. As a result of the latch dogs pivoting outwardly to a latching position, the locking pin 75 is free to move into the latch dog cut outs 16a, 16b; and finally, the latch release tube under the resilient action of spring 80 (and/or gravity if the drilling direction is downwardly) moves inwardly relative to the latch body to abut against the shoulder 65 of the latch body. This inward movement of the latch release tube allows the plug 104 to move inwardly to abut against the head of the bolt 77 in the event it was previously spaced therefrom. Due to the provision of the elongated slot 105 and the fact that the latch release tube moves inwardly a substantially greater axial distance than any spacing between the adjacent surfaces of the head of the bolt 77 and the plug at this time, the plug in abutting against the bolt prevents further movement of the plug inwardly even though the latch release tube moves axially inwardly. As a result the outer annular edge 27a of the latch release tube moves away from the washer 112 a substantial axial distance as illustrated in FIGURE 8. Since the edge 27a no longer bears against the washer 112, the fluid pressure acting in the direction of arrow 124 causes the leather washer to flex inwardly to the position of FIGURE 8. As a result, an annular clearance space is provided between the leather washer and the inner peripheral wall of the drill stem substantially the same size as the main portions of the annular clearance space between the latch release tube and the corresponding inner peripheral wall of the drill stem.

In the event during the core taking operation, the drill bit should extend into a high pressure pocket of fluid, the back pressure of said fluid would flow through the core bit aperture, thence through the annular clearance space between the core barrel inner tube and the drill stem, thence through the bypass channel provided by port 55, 40 56 and bore 50 and outwardly through the annular clearance space between the latch release tube and the drill stem. Due to fluid back pressure acting in a direction opposite the arrow 124, the outer annular portion of the washer 112 is flexed outwardly to a limiting position of 45 abutting against the beveled surface 116a of the retainer nut (see dotted line position of FIGURE 8) and thereby provides an annular clearance space adjacent the washer of substantially the same area as that of the solid line normal operating position illustrated in FIGURE 11. Due 50 to the aforementioned annular clearance space, there is no substantial force component acting solely against the latch release tube and/or the valving member of sufficient strength to overcome the resilient action of the spring 80, this being in contrast to where the valving member or 55 latch release member has a non-flexible enlarged portion that closes the clearance space between the core barrel inner tube assembly and the drill stem. Accordingly, no substantial movement of the latch release tube takes place and therefore the locking pin 75 prevents the latch dogs 60 from pivoting out of latching engagement with the latch seat.

Assuming that the core barrel inner tube has been filled with core and it is desired to retract the core barrel inner tube assembly 100 from the bit end of the drill stem; a hydraulically propellable overshot assembly is fluidly propelled towards the bit end of the drill stem until the pulling dogs clampingly engage the spear point 110. Advantageously the overshot assembly used for retracting the core barrel inner tube assembly 100 is the same as that described with reference to the overshot 75

assembly illustrated in FIGURES 12-14, the operation of which will be described hereinafter.

After the overshot assembly has been fluidly propelled to position to clampingly engage the spear point 110, the wire line is retracted to thereby retract the overshot assembly and the valving member 104, 116, and 112. In the event that the inner transverse edge of the slot 105 is not abutting against the pin 87, the initial retraction of the overshot assembly moves plug 104 to such a position. If the overshot assembly is of a construction that fluid bypasses it while it is being retracted, the leather washer 112 under the action of the relative motion to the fluid will cause said washer to remain in generally the condition illustrated in FIGURE 8. At this time further retraction of the plug 104 moves the latch release tube axially outwardly relative to the latch body and thereby moves the locking pin axially outwardly from the latch dog cut outs to a position outwardly of the latch dog edges 16e. After the locking pin has been moved out of the cut outs, the beveled edges of the latch release tube abut against the diagonal edges of the latch dogs to force them to pivot out of the latch seat; the latch release tube being movable relative to the latch body unit, the body pin 75 abuts against the inner edge of the slots 74. At this time the adjacent surfaces of the plug and the head of the bolt 77 have been moved apart to relative positions such as illustrated in FIGURE 10. However it is to be understood that if assembly 100 is being retracted in a generally downward direction and/or depending on the characteristics of spring 80, it is possible for the latch body to move relative the latch release tube until the locking pin abuts against the latch dog edges 16e and accordingly position the head of bolt 77 much closer the plug 106 than that illustrated in FIGURE 10. Further retraction of the overshot valve results in the entire core barrel inner tube assembly being retracted through the drill stem while at the same time due to the flexing of the leather washer, fluid can bypass assembly 100 as it is being retracted in a manner corresponding to its bypassing the assembly during the core drilling operation.

The usage of the second embodiment of the core barrel inner tube 100 having been described, the operation of the overshot assembly 125 of FIGURES 12-14 will now be set forth. As previously indicated, the overshot assembly 125 is of a construction that is hydraulically propellable to the bit end of the drill stem regardless of the drilling direction. When the core barrel inner tube assembly is first inserted in the drill stem and if there is no, or low tensile force being applied through the wire line 159 at the coupling element, the resilient action of the coil spring 150 acting through the rod 144b will move the valving member relative tube 139 to a position that the outer transverse edge of the slot 145 abuts against the pin 143 such as illustrated in FIGURE 12. At this time the flexible leather washer 156 is positioned to abut against the outer annular edge 139a of tube 139 while extending generally radially outwardly from the shoulder 154 of the fitting. As a result, the outer circumferential edge of the washer bears against the drill stem to at least substantially, if not completely, form a fluid seal therewith to prevent fluid under pressure bypassing the overshot assembly at this location in the direction of arrow 124. In the event the drilling direction is vertically downwardly, the spring 150 holds the tube 139 in abutting engagement with the leather washer as illustrated, the characteristics of the spring being such to accomplish this result. Fluid under pressure is pumped into the outer axial end of the drill stem to act against the outer annular surfaces of the coupling 158 and the exposed surfaces of the leather washer 156 to fluidly propel the overshot assembly through the drill stem in the direction of arrow 124. Upon the overshot assembly being moved adjacent the spear point of the core barrel inner tube assembly, the jaws 132 are forced apart to be passed

over the spear point of the overshot assembly, and thence under the action of spring 134 move together to clampingly engage the spear point of the core barrel inner tube assembly that is to be withdrawn. Now the wire line 5 is retracted (moved in a direction opposite arrow 124) and thereby retracts the coupling element 158, the fitting 144 and the washer 156 relative the tube 139, the core barrel inner tube assembly being latched in position and thereby opposing the retraction of the tube 139 and the elements connecting the tube to the latch dogs. The initial retraction of the fitting moves it relative the pin 143 against the resilient action of spring 150 to a position that the inner transverse edge of the slot 145 abuts against said pin (see FIGURE 13). Further retraction of 10 the wire line transmits the pulling force directly through the coupling element and fitting 144 to the pin 143 and thence to the tube 139 to retract the latch release tube, for example, in the manner described heretofore. To be noted is that the retraction of the fitting 144 relative the tube 139 moves the leather washer 156 axially outwardly of the outer annular edge of the tube 139 and thereby provides a clearance space for the outer annular edge portion of the washer to flex inwardly such as illustrated in FIGURE 13. This provides an annular clearance space adjacent the washer to permit fluid bypassing the overshot assembly as it is being retracted. Accordingly fluid in the drill stem can readily bypass the overshot assembly during the retraction thereof; and if the core barrel inner tube assembly is of a construction to 20 permit fluid bypassing it as it is being withdrawn, fluid is not forced out of the drill stem as the overshot assembly and wire line core barrel inner tube assemblies are being retracted.

Referring to FIGURE 15 there is shown a fragmentary 35 outer end portion of a fluidly propellable core barrel inner tube assembly generally designated 170. The assembly 170 is of the same construction as assembly 100 other than for the differences noted hereinafter. The assembly 170 includes a latch release tube 27 together with 40 a plug generally designated 171 that has a rectangular slot 177 through the main body portion 172. The inner transverse surface of the plug is flat such as illustrated for plug 104. A pin 87 connects plug 171 to the release tube 27. Plug 171 also includes a reduced diameter threaded portion 173 and a non threaded portion 174 of about 45 the same diameter as portion 173 which integrally joins the main body portion to said threaded portion. At the juncture of portions 172, 174 there is provided a somewhat axially inwardly inclined, generally radially extending annular surface 175.

A flexible resilient member 178, such as a leather washer, having an inside diameter about the same as portion 50 174 is forced over portion 174. As may be noted from FIGURE 15, when the outer transverse edge of the slot 177 bears against pin 87, the flexible member 178 abuts against the tube 27 and at the outer peripheral portion forms a fluid seal with the drill stem.

An annular retainer 180 is threaded on portion 173, said retainer having an outer cylindrical surface that is 55 substantially the same as the outside diameter as tube 27. The retainer has an annular frusto-conical surface 180a that is inclined radially outwardly and axially inwardly from the elongated axis of assembly 170, and has an annular frusto conical surface 180b inclined radially outwardly and axially outwardly from surface 180a to provide a clearance space into which the outer peripheral portion of member 178 may be flexed. At the juncture of surfaces 180a and 180b there is formed an annular ridge to bear against the flexible member radially outwardly of portion 174 to clamp said flexible member against the outer peripheral part of surface 175.

The plug also includes a spear point 182 that is threaded on the reduced diameter portion 173, said spear point having a main body portion 182a that has a cylindrical 60 surface of a diameter substantially the same as the maxi-

mum diameter of retainer 180, an axially intermediate reduction diameter portion 182b and a conical point. The spear point upon being threaded on plug portion 173 bears against the retainer to lock it in place, said retainer compressing the flexible member between it and the main body portion 172.

Due to the provision of the ridge formed by surfaces 180a, 180b, the flexible member is more firmly clamped in position than that obtained with, for example, assembly 100. Also since the spear point 182 and retainer are removable from the remaining portion of plug 171, the inside diameter of flexible member 178 may be substantial smaller than that of member 112 which has to be slipped over the spear point of plug 104. As a result, with plug 171, a greater annular portion of the flexible member 178 is located transversely inwardly of the outer circumferential surface of the latch release tube even though both of said members 112, 178 have the same size outside diameter. Also due to the shape of surfaces 180a, 180b and 175, the flexible member is more firmly held on the plug than member 112 on its plug. The operation of assembly 170 is the same as that of assembly 100; it will not be described.

Referring to FIGURES 16 and 17, there is illustrated the upper end portion of core barrel inner tube assembly 10, the lower end portion of an overshot assembly 191, and an overshot release tube 192. Since the overshot assembly may be of the same construction as that described in U.S. Patent 3,120,282, granted Feb. 4, 1964 (see FIGURES 22, 23) other than for the shape of the pulling dogs, the structure of the lower end portion of assembly 191 will be briefly described herein.

The overshot assembly includes an overshot body 193 having a pair of pulling dogs 194 pivotally mounted in a slot milled therein by a pivot pin 195 such that said dogs are oppositely faced. The outer end portion 193a of body 193 is of a sufficiently reduced diameter that the release tube may be slideably positioned thereon and abut against the outer transverse edges 194b of said dogs when they are in a spear point clamping position. The dogs are resiliently retained in such a clamping position by a coil spring 197 that at opposite ends is positioned on pins 198 secured to the adjacent outer end portions of said dogs, i.e. on the ends opposite jaws 194a with pin 195 between spring 197 and the jaws. However in the event the frusto conical surface 84d of plug 84 is moved axially outwardly relative the jaws 194a of the pulling dogs when said dogs are clampingly coupled onto the plug 84, for example, through jarring or a hammering blow, the frusto conical portion 84d forces the jaws apart and causes the dogs to pivot about pin 195 such that there outer ends move more closely adjacent one another. If the drilling direction is at a sufficiently downwardly angle, the release tube 192 under action of gravity will move axially relative said dogs to a position that the dogs are prevented from returning to a clamping position (see FIGURE 17) even though the plug surface 84d has moved axially inwardly of said jaws. As a result the core barrel inner tube assembly is released from being couplingly attached to the overshot assembly. To facilitate the inward movement of the release tube 192 relative the pulling dogs, the interior, axially inner, surface thereof is beveled at 192a such as illustrated in FIGURE 16.

The aforementioned releasing is desirable when the core barrel inner tube assembly has been lowered to a position to engage the drill stem latch seats or said assembly is jammed in the drill stem and it has been decided to retract the overshot assembly without the core barrel inner tube assembly.

However in dry hole drilling in a downwardly direction, where it is desired to lower a conventional core barrel inner tube assembly through the use of an overshot assembly and release the overshot assembly from said core barrel inner tube assembly, at times the core barrel inner tube assembly will temporarily be "hung up" at an

immediate portion of the drill stem, for example, catching at a drill stem pipe joint. This frequently results in the core barrel inner tube assembly being prematurely released by the overshot assembly in a manner described above; and as a result the core barrel inner tube assembly free falls and on reaching the bit end of the drill stem the abrupt stop will result in damage to either the outer tube assembly or the inner tube assembly. Applicants have through their invention of structure such as illustrated in FIGURES 1-6 have overcome this problem as will be described hereinafter.

The plug 84 has a minimum diameter portion 84e that at one end is integrally joined to the base of spear point 88 and at the opposite end to the minor base of frusto-conical portion 84d. The diameter of reduced diameter portion 84e is such that when the jaws are clamping retaining the plug (such as in FIGURE 16) the edges of the jaws may abut against portion 84e, and at the same time dog edges 194b will hold the release tube 192 against inward movement relative dogs 194. Thus under normal core barrel inner tube assembly lowering conditions, the pulling dogs will support the weight of assembly 10, this resulting in the various part of the assembly 10 moving relative one another to a position such as illustrated in FIGURE 4. That is since the overshot assembly supports the weight of assembly 10 (holds it against "free fall") and plug 84 is slidingly attached to the latch release tube 27 by a pin in slot 86, the latch release tube and the structure depending therefrom will move relative the plug such that pin 87 bears on the inner transverse edge of slot 86.

In the event during the lowering operation, assembly 10 should, for example, lodge on a pipe stem joint, the various members of assembly 10 are free to, and will under gravity, move relative to one another to a position such as illustrated in FIGURE 5. In this connection note that plug 84 is free to, and does, move axially inwardly until surface 84a abuts against bolt 77 wherein the major base part of frusto conical portion 84d is located within the confines of the latch release tube (see FIGURES 5 and 16). At the same time the inward movement of the overshot assembly relative assembly 10 is limited by inner shoulder 193c of the overshot body abutting on the outer annular surface 27c of the latch release tube whereby the jaws 194a are for the most part diametrically opposite reduced diameter portion 84e. Further the tube 27 can not at this time move further inwardly relative bolt 77 since pin 75 abuts against edges 16a of the latches 16. As a result jaws 194 still clampingly retain plug 84 and the overshot release tube 192 still abuts against edges 194b. Thus by retracting the overshot assembly with a wire line (not shown), the core barrel inner assembly 10 may be raised to dislodge it from a pipe joint.

When the core barrel inner tube assembly is latched in position as indicated relative FIGURES 1-3, pin 75 moves down into slot 16a, 16b and the latch release tube moves downwardly relative bolt 77. Further the overshot body is free to move downwardly relative bolt 77 the same distance as the latch release tube. However, since plug 84 will abut against pin 87, tube 27 moves relative plug 84 such that the frusto conical portion 84d is located outwardly of the confines of tube 27 so as to force jaws 194a apart a distance greater than the maximum diameter of point 88 (see FIGURE 17). This results in the outer ends of the dogs 194 moving together sufficiently that release tube 192 moves axially inwardly relative thereto to prevent the dogs pivoting about pin 195. At this time the wire line (not shown) is retracted to retract the overshot assembly while leaving assembly 10 in a latched core receiving position.

Tube 192 may be of the same construction as that disclosed in the aforementioned U.S. Patent 3,120,252 (FIGURES 22, 23); or may be of the same construction other than that the end wall 182 of said patent is eliminated.

An advantage of the second embodiment of the wire line core barrel inner tube assembly 10 over the first embodiment, is that the assembly 100 may be fluidly propelled to the bit end of the drill stem regardless of the drilling direction. A further advantage of the second embodiment of the wire line core barrel inner tube assembly and also of the overshot assembly 125 over that of the prior art is that there is provided means for resiliently retaining the latch release tube and the valving member respectively in positions that a fluid seal is formed with the drill stem during the pump in operation.

As an example of the further construction of the washer 112, if it is to be used with a series of core barrel equipment wherein the drill stem inside diameter is $1\frac{3}{16}$ inches and the washer is of leather, advantageously the washer has an axial thickness of approximately $\frac{3}{32}$ ", and outside and inside diameters of approximately $1\frac{3}{16}$ " and 1" respectively. With this particular series, the outside diameter of the latch release tube would be approximately $1\frac{1}{16}$ inches. Preferably the aperture in the washer through which plug portion 107 extends is drilled rather than punched as punching breaks the grain structure and a punched washer when wet expands somewhat away from portion 107. Also a leather washer wears better if the grain side of the leather is toward the bit end of the drill stem and the flesh side faces toward the pump end of the drill stem. However as previously indicated, flexible materials other than leather may be used.

As many widely apparently different embodiments of this invention may be made without departing from the spirit and scope thereof, it is to be understood that we do not limit ourselves to the specific embodiments herein.

What we claim is:

1. In core drilling apparatus that includes a drill stem having a hollow bit end located in a hole drilled in the earth and a latch seat axially spaced from said bit end, a core barrel inner tube assembly comprising means for collecting a core sample, a fitting connected to the core sample means to extend axially therefrom, detent means mounted by said fitting for movement between a position latchingly engaging said latch seat and a retracted position, said detent means including a pair of latches pivotally mounted on said fitting, latch release means mounted by the fitting for limited axial slidable movement between a first position and a second position more remote from said core sample means, said detent means being positioned to move to a retracted position when said release means is moved to its second position, means mounted on the release means for movement therewith to in the release means first position lock said detent means in a latch seat engaging position and in a release means second position permit the detent means being moved to a retracted position, said latches having axially outer, adjacent corners that have oppositely faced cut outs of a size and shape to have the locking means move thereinto when the latches are in a latch seat engaging position to retain said latches in the latch seat and in the latch retracted position block the lock means from moving into said cut outs, said latch release means including a tube having slots for the latches to extend through in a latch seated position, said fitting includes a reduced diameter portion extended into said tube that mounts said latches and has an axially elongated slot for the locking means to extend through, the length of the last mentioned slot in conjunction with said locking means limiting the movement of the latch release means relative the fitting to movement between said latch release means first and second positions, first means mounted on the fitting for resiliently urging said release means to its first position, and second means for resiliently urging the detent means toward the latch seat engaging position, said second resilient means comprising a spring having opposite ends connected to the respective latch to resiliently urge said latches to pivot in opposite directions.

2. The structure of claim 1 further characterized in that said latch release means includes an overshot coupling plug

slidably extended into the outer end of said tube and means cooperating with the plug to attach said plug to said tube for limited axial movement relative thereto.

3. The structure of claim 2 further characterized in that said tube is of an outside diameter to provide an annular clearance between it and the adjacent inner peripheral wall of the drill stem, that the plug extends axially outwardly of the latch release tube, and that the outside diameter of said tube is greater than any portion of the assembly that extends axially outwardly thereof.

4. The structure of claim 2 further characterized in that said tube is of an outside diameter to form an annular clearance space with the adjacent inner peripheral wall of the drill stem, that the latch release means includes a valving member attached to said tube for limited axial movement relative thereto, said valving member including a plug slidably extended into said tube, means mounting said plug on said tube for movement between an inner and an outer position and flexible means mounted on said plug for in a plug inner position substantially forming a fluid seal with the adjacent wall of the drill stem and in a plug outer position flexing under fluid pressure to provide a generally annular clearance fluid bypass space.

5. The structure of claim 4 further characterized in that said first means includes an axially elongated member attached to said fitting for movement therewith, to extend axially away from said fitting within said tube and of a length to with the release means in its first position abut against said plug to retain it adjacent its outer position relative said tube.

6. The structure of claim 4 further characterized in that there is provided a wire line core barrel overshot assembly for retracting said core barrel inner tube assembly through the drill stem, said overshot assembly comprising means for releasably clasping said overshot coupling plug, an outwardly extending overshot fitting mounting said clasping means and a valving portion including a wire line coupling member, means for attaching said coupling member to said overshot fitting for limited axial movement between a first position and an inwardly second position, means co-operatively mounted by the last mentioned means and the overshot fitting for resiliently urging said coupling member attaching means to its second position, said coupling member and overshot fitting being of transverse dimensions and shape to provide a fluid bypass channel within the drill stem, and overshot flexible means mounted by said attaching means to in co-operation therewith substantially form a fluid seal with the drill stem to restrict the flow of fluid bypassing the overshot assembly when the attaching means is in its second position, said overshot flexible means being positioned by the attaching means to abut against said overshot fitting and to in the attaching means first position, flex in the direction of flow of fluid under pressure to permit fluid to bypass said overshot assembly and a wire line attached to said coupling member to move it outwardly and thereby move said attaching means to its first position.

7. In apparatus for fluidly controlling the movement of a core barrel inner tube through a drill stem, an axially elongated member of a transverse cross section to be received in the drill stem to form a fluid bypass channel therewith, and at least the outer end thereof having an axially extending opening, a plug having a portion extended into said opening, means attaching said plug to the elongated member for limited relative axial movement between a first position and an outer second position, flexible means on said plug to in said first position abut against said elongated member and in cooperation with said plug substantially form a fluid seal with the drill stem, and in said second position flex under fluid pressure to provide a clearance space with said drill stem to permit fluid to bypass the plug and elongated member and means of a size and shape to provide a fluid clearance space with the drill stem mounted on said plug on the opposite side of the flexible means from said elongated member.

gated member to cooperate with the plug for mounting the flexible means for movement with the plug.

8. The apparatus of claim 7 further characterized in that said elongated member has an annular outer end portion and that said flexible means is an annular member that has a maximum outside diameter approximately the same as the inside diameter of the drill stem.

9. The apparatus of claim 8 further characterized in that the last mentioned means mounted on the plug has a surface beveled radially outwardly in an axially outwardly direction adjacent the annular member to provide a clearance space for the outer annular portion thereof to flex into when fluid under pressure in the drill stems exerts a sufficiently high force in an axially outward direction.

10. The structure of claim 8 further characterized in that said plug has a reduced diameter end portion and a main body portion joined thereto to form a shoulder, said annular member being a leather washer abutting against said shoulder, said main body portion being slidably extended into said opening to in a plug first position, position said shoulder radially adjacent the outer edge of said annular outer end portion with the annular member in abutting relationship therewith, said annular outer end portion being of a small diameter than the drill stem to provide a fluid bypass space with the drill stem.

11. The structure of claim 8 further characterized in that there are provided an overshot body attached to elongated member on the end portion axially opposite said plug and means mounted on said overshot body axially opposite the elongated member for coupling onto a core barrel inner tube assembly having the core barrel inner tube and means interconnecting the elongated member and the plug to resiliently urge said plug and the elongated member to relatively move to their first position, said overshot body and coupling means in conjunction with the drill stem cooperatively providing a fluid bypass space.

12. The structure of claim 11 further characterized in that said resilient urging means includes an abutment attached inside of said tube, a stem joined to said plug portion to move therewith and slidably extended through said abutment and spring means connected to said stem and bearing against said abutment for resiliently urging said stem toward said coupling means and that there is provided wire line means attached to said plug for moving it to its second relative position.

13. The structure of claim 7 further characterized in that the drill stem has a rotary core bit at the inner end thereof and a latch seat adjacent the core bit, that there is provided means for receivingly holding a core sample, a fitting attached to the core barrel inner tube to extend axially outwardly thereof, and detent means mounted by the fitting for movement between a retracted position and an extended position to engagingly seat in said latch seat, said elongated member and fitting having cooperating means for attaching the elongated member to the fitting for limited relative axial movement between a first position releasably locking the detent means in a detent means extended position and a second position releasing the detent means to move to a retracted position, said detent means being mounted by the fitting adjacent said elongated member, said core barrel inner tube and fitting cooperatively providing with the drill stem a fluid channel extending from said elongated member to the inner end of the core barrel inner tube.

14. The structure of claim 13 further characterized in that said fitting includes a latch body having the detent means mounted thereon and that there is provided means connected to said latch body and said elongated member for resiliently urging the elongated member to move relative the fitting to a detent means locking position, the means connected to the latch body including axially elongated means attached to the latch body to move therewith and extended into said elongated member opening for forcing said plug to its second position as the fitting and

the elongated member relatively move to a detent means locking position.

15. The structure of claim 14 further characterized in that the latch body has a reduced diameter portion mounting said detent means, that said detent means includes a latch, that said elongated member includes a latch release tube extended over said reduced diameter portion and has a latch retracting slot for the latch to extend through in a latch seated position and is movable between said detent means locking position and said detent means releasing position, and that there is provided means on the reduced diameter portion for resiliently urging the latch to a latch seat engaging position.

16. The structure of claim 15 further characterized in that said latch has a notched cut out opposite the portion that engages the latch seat and that the fitting and elongated member cooperating means includes a transverse pin attached to the latch release tube for movement therewith between said detent means locking position to enter into said cut out to retain the latch in a latch seated position and a position axially outwardly of said cut out.

17. For core drilling apparatus that includes a drill stem having an apertured core bit at one end and a latch seat axially spaced from said bit, an elongated core barrel inner tube assembly comprising means for collecting a core sample, an axially elongated latch body, means for connecting adjacent end portions of the core collecting means and the latch body, detent means mounted by said latch body for movement between an extended position to seat in said latch seat when the core collecting means is adjacent said bit and a retracted position free of said latch seat, means for urging said detent means to an extended position, axially elongated means slidably mounted by the latch body to move axially outwardly relative thereto for releasing said detent means and to an inner relative axial position, said release means having a portion for retracting said detent means as the release means is moved to an outer position, and including a generally tubular member slidably mounted on the latch body that has a slot for the detent means to extend through, means attached to said release means for movement therewith to in cooperation with the latch body limit the axial movement of the releasing means between the axially inward position and an axial outward position and in the releasing means inward position with the detent means in an extended position lock said detent means in engagement with the latch seat until the releasing means has been at least moved to its outward position, an overshot coupling device attached to the outer end portion of said release means, said overshot coupling device being slidably extended into said tubular member, means acting in cooperation with said overshot coupling device mounting said coupling device on the tubular member for limited relative axial movement between an inner axial position and an outer axial position, an elongated spring mounting member attached to the latch body to extend axially outwardly of the latch body and within the said tubular member, and spring means acting in cooperation with said spring mounting member to resiliently urge said tubular member axially inwardly relative to said latch body, said spring mounting member being of a length to limit the inward movement of the coupling device toward its inner axial position relative to said tubular member when said tubular member moves to its inward position relative the latch body.

18. The structure of claim 17 further characterized in that said coupling device in each of its axial positions has a portion extending axially outwardly of said tubular member and that all portions of said assembly have a maximum cross sectional area smaller than the area enclosed by the outer perimetric cross sectional border of tubular member.

19. The structure of claim 17 further characterized in that said coupling device in each axial position has a portion extending axially outwardly of said tubular mem-

ber, and that there is provided flexible means mounted on said coupling device and movable therewith for abutting against the outer annular edge of said tubular member and substantially form a fluid seal with the adjacent inner peripheral wall portion of the drill stem when the coupling device is in its inward position relative the tubular member and in the coupling device outer position relative said tubular member flex under fluid pressure to permit fluid in the drill stem to bypass it.

20. In core drilling apparatus that includes a drill stem having a hollow bit end located in a hole drilled in the earth and a latch seat axially spaced from said bit end, a core barrel inner tube assembly comprising means for collecting a core sample, a latch body, means for connecting adjacent ends of the latch body and the core sample collecting means, detent means mounted by said latch body for movement between an extended position to seat in said latch seat when the core sample collecting means is adjacent said bit end, and a retracted position clear of said latch seat, an elongated mounting member fixedly attached to the latch body to move therewith and to extend outwardly therefrom, means slidably mounted by the latch body for movement to an axially outward position relative the latch body to retract said detent means and an axially inward position to permit said detent means moving to an extended position, an overshot coupling member attached to the release means opposite the latch body and means acting against said mounting member and the release means for urging said release means to its axially inward position.

21. In core drilling apparatus that includes a drill stem having a hollow bit end located in a hole drilled in the earth and a latch seat axially spaced from said bit end, a core barrel inner tube assembly comprising means for collecting a core sample, a latch body having an axially elongated slot means for connecting adjacent ends of the latch body and the core sample collecting means, detent means mounted by said latch body for movement between an extended position to seat in said latch seat when the core sample collecting means is adjacent said bit end, and a retracted position clear of said latch seat, said detent means including an elongated pair of latch dogs, means for pivotally attaching the one end of the latch dogs to the latch body, and a spring having one end attached to the opposite end of one latch dog and a second end attached to the opposite end of the other latch dog for resiliently urging the latch dogs to the detent means extended position, an elongated mounting member attached to the latch body to move therewith and to extend outwardly therefrom, release means slidably mounted by the latch body for movement to an axially outward position relative the latch body to retract said detent means and an axially inward position to permit said detent means moving to an extended position, said release means including a transverse pin extended through said slot, and said latch dog opposite ends in a detent means extended position having adjacent cut outs that said pin enters into to releasably lock said latch dogs in a latch seated position and outer transverse edges against which said pin abuts until said latch dogs have moved to a latch seated position, an overshot coupling member attached to the release means opposite the latch body and means acting against said mounting member and the release means for urging said release means to its axially inward position.

22. The structure of claim 21 further characterized in that coupling member is attached to the release means for limited axial movement between an inner axial position and an outer axial position and in both positions extends outwardly of said release means, flexible means mounted on the coupling member for movement therewith to in the coupling member inner axial position abut against release means and substantially form a fluid seal with the drill stem and to flex under fluid pressure to form a fluid clearance space with the drill stem when the coupling

member is adjacent its outer axial position, said mounting member being of a length to stop said coupling from moving to its inner axial position when the release means is in its inner position relative the latch body, said assembly other than for said flexible means in cooperation with said drill stem being of a construction to form a fluid bypass channel from one axial end of said assembly to the other.

23. An overshot assembly for retracting a core barrel inner tube assembly having an overshot coupling member through a drill stem comprising an axially elongated overshot body, means mounted on one end of the overshot body for releasably coupling onto said coupling member, valving means in an inner position forming a fluid seal with the drill stem and an outward position providing a fluid clearance space therewith, means for attaching said valving means to the overshot body for movement between said positions, means cooperating with said attaching means and the valving means for resiliently urging the valving means to said inner position, and wire line coupling means attached to said valving means for moving the valving means to said outward position, said overshot assembly other than for said valving means in a fluid seal condition in conjunction with the drill stem being of a construction to form a fluid bypass channel from one axial end of the overshot assembly to the other.

24. The structure of claim 23 further characterized in that the attaching means has a smaller outside diameter than the inside diameter of the drill stem to provide a fluid bypass space and includes an outer end portion having an axial opening, that said valving means includes a plug having a main body portion slidably extended into said opening and a reduced diameter outer end portion, an annular flexible member mounted on said reduced diameter end portion in abutting relation with said main body portion, and means for retaining said annular member on the plug for axial movement therewith, said plug mounting said annular member to abut against the outer edge of said outer end portion in the valving means inner position whereby the overshot assembly may be fluidly propelled to the bit end of the drill stem regardless of the drilling direction.

25. In apparatus for fluidly controlling the movement of a core barrel inner tube through a drill stem, an axially elongated member of a transverse cross section to be received in the drill stem to form a fluid bypass channel therewith, and having an outer annular end portion with an axially extending opening, a plug having a portion extended into said opening, means attaching said plug to the elongated member for limited relative axial movement between a first position and an outer second position, flexible means on said plug to in said first position abut against said elongated member and in cooperation with said plug substantially form a fluid seal with the drill stem, and in said second position flex under fluid pressure to provide a clearance space with said drill stem to permit fluid to bypass the plug and elongated member, said flexible means being an annular member that has a maximum outside diameter approximately the same as the inside diameter of the drill stem, and means of a size and shape to provide a fluid clearance space with the drill stem mounted on said plug on the opposite side of the flexible means from said elongated member to cooperate with the plug for mounting the flexible means for movement with the plug, said plug having a main body portion located within said opening, and a spear point integrally joined to said main body portion to be located axially outwardly of said elongated member.

26. In apparatus for fluidly controlling the movement of a core barrel inner tube through a drill stem, an axially elongated member of a transverse cross section to be received in the drill stem to form a fluid bypass channel therewith, and having an outer annular end portion with an axially extending opening, a plug having a portion ex-

tended into said opening, means attaching said plug to the elongated member for limited relative axial movement between a first position and an outer second position, flexible means on said plug to in said first position abut against said elongated member and in cooperation with said plug substantially form a fluid seal with the drill stem, and in said second position flex under fluid pressure to provide a clearance space with said drill stem to permit fluid to bypass the plug and elongated member, said flexible means being an annular member that has a maximum outside diameter approximately the same as the inside diameter of the drill stem, and means of a size and shape to provide a fluid clearance space with the drill stem mounted on said plug on the opposite side of the flexible means from said elongated member to cooperate with the plug for mounting the flexible means for movement with the plug, said plug having a main body portion located within said opening, a reduced diameter portion extended through means mounted on the plug to cooperate therewith and a spear point member removably mounted on said reduced diameter portion to be located axially outwardly of said flexible means.

27. For core drilling apparatus that includes a drill stem having an apertured core bit at one end and a latch seat axially spaced from said bit, an elongated core barrel inner tube assembly comprising means for collecting a core sample, an axially elongated latch body, means for connecting adjacent end portions of the core collecting means and the latch body, detent means mounted by said latch body for movement between an extended position to seat in said latch seat when the core collecting means is adjacent said bit and a retracted position free of said latch seat, means for urging said detent means to an extended position, axially elongated means slidably mounted by the latch body to move axially outwardly relative thereto for releasing said detent means and to an inner relative axial position, said release means having a portion for retracting said detent means as the release means is moved to an outer position and an axially elongated opening into which the outer end portion of the latch body extends, means attached to said release means for movement therewith to in cooperation with the latch body limit the axial movement of the releasing means between the axially inward position and an axial outward position and in the release means inward position with the detent means in an extended position lock said detent means in engagement with the latch seat until the release means has been at least moved to its outward position, means mounted by said latch body outer end portion and the releasing means for resiliently urging said releasing means to its inner relative axial position, and an overshot coupling device attached to the outer end portion of said release means:

28. In wire line core barrel apparatus that includes a drill stem having a core bit and a latch seat axially spaced from said bit, a core barrel inner tube assembly comprising means for collecting a core sample, a fitting connected to the core sample means to extend axially therefrom, detent means mounted by said fitting for movement between a position latching engaging said latch seat to releasably retain the fitting and thereby the core sampling means adjacent said bit and a retracted position, release means mounted on the fitting for axial sliding movement relative the fitting between a first position and a second position more axially remote from said core sample means to release the detent means from latching engaging said latch seat, means for connecting the release means to the fitting to in cooperation with the fitting limit the axial movement of the release means relative the fitting between its first and second positions, co-acting with the detent means to lock said detent means in a latch seat engaging position when the release means is in its first position, and permitting the detent means moving to a retracted position when the release means is moved toward its second position, first means mounted on

the fitting for resiliently urging said release means toward its first position, and second means for resiliently urging said detent means to a latch seat engaging position.

29. The apparatus of claim 28 further characterized in that said means for connecting the release means to the fitting comprises a transverse member and that the fitting has an axially elongated slot, said transverse member being extended through said slot and said slot being of a length to in conjunction with said transverse member limit the movement of said release means relative the fitting between said release means first and second positions.

30. The core drilling apparatus that includes a drill stem having an apertured core bit at one end and a latch seat axially spaced from said bit, an elongated core barrel inner tube assembly comprising means for collecting a core sample, an axially elongated latch body, means for connecting adjacent end portions of the core collecting means and the latch body, detent means mounted by said latch body for movement between an extended position to latching engage said latch seat when the core collecting means is adjacent said bit and a retracted position free of said latch seat, axially elongated release means slidably mounted by the latch body to move to a first position axially outwardly relative said latch body for releasing said detent means from latching engagement with the latch seat and to an inner relative axial second position, means fixedly attached to said release means to move therewith for acting in cooperation with the latch body to limit the axial movement of the release means outwardly relative the latch body to the axial outward position and in the release means inward position act in cooperation with the detent means in an extended position to lock said detent means in engagement with the latch seat until the release means has been at least moved toward its outward position, and an overshot coupling device attached to the outer end portion of said release means.

31. The apparatus of claim 30 further characterized in that the means fixedly attached to the release means comprises a transverse member and that said detent means includes an elongated latch having a cut out portion and a transverse edge adjacent said cut portion and means connected to the latch body for mounting said latch for movement between said detent means retracted position to position said transverse edge in abuttable relationship with said transverse member to prevent the release means moving to its first position, and said detent means extended position to position said cut out to permit the transverse member moving into said cut out and thereby permit the release means moving to its first position.

32. The apparatus of claim 31 further characterized in that said latch body has an axially elongated slot, said transverse member extending into said slot, said slot being of a length to in conjunction with said transverse member limit the slideable movement of said release means relative said latch body and that there is provided means for resiliently urging said latch to said detent means extended position.

33. In core drilling apparatus that includes a drill stem having a hollow bit end located in a hole drilled in the earth and a latch seat axially spaced from said bit end, a core barrel inner tube assembly propellable by fluid through the drill stem and permitting fluid to bypass it when it is adjacent the bit end comprising means for collecting a core sample, a fitting connected to the core sample means to extend axially therefrom, detent means mounted by said fitting for movement between a position latching engaging said latch seat to retain the assembly adjacent the bit end and a retracted position, release means mounted on the fitting for limited axial movement relative the fitting between a first position and a second position more axially remote from the core sample means to release the detent means from latching engaging the

latch seat, said release means having a release member movable between said release means positions and means for acting in cooperation with the detent means in a retracted position for retaining the release member from movement to its first position, first means mounted on the release means for limited movement relative thereto to in one position relative the release means cooperate with the release means in its second position to substantially form a fluid seal with the drill stem and in a second position relative the release means permit fluid to more readily bypass said assembly, and second means attached to the fitting for movement therewith to move said first means from its one position to its second position as the release means moves to its first position and to resiliently urge said release means to its first position.
